UNITED STATES PATENT OFFICE.

GEORGE A. WEBER, OF NEW YORK, N. Y., ASSIGNOR TO THE WEBER RAILWAY JOINT MANUFACTURING COMPANY, OF NEW YORK, N. Y., A CORPORATION OF WEST VIRGINIA.

INSULATED JOINT FOR RAILROAD-RAIL SECTIONS.

SPECIFICATION forming part of Letters Patent No. 738,862, dated September 15, 1903.

Application filed September 20, 1902. Serial No. 124,193. (No model.)

To all whom it may concern:

Be it known that I, GEORGE ADAM WEBER, a citizen of the United States, residing in the city, county, and State of New York, have invented certain new and useful Improvements in Insulated Joints for Railroad-Rail Sections, of which the following is a full, clear, and exact description, accompanied by drawings.

The object of this improvement is to produce a more efficient insulated joint for railroad-rail sections, which shall not require insulation between the webs of the rails and the bolts which secure the parts together at those points where said bolts pass through said webs.

I will describe a joint embodying the improvement in the best form now known to me and then point out the novel features in the claims.

In the accompanying drawings, Figure 1 is a transverse section of a railroad-rail joint embodying my improvement, and Fig. 2 is a top view of the same.

A' A^2 designate railroad-rail sections of any suitable form arranged in line.

B' designates an angle-chair, preferably made of rolled steel and comprising a base b' and an upright b^2 , preferably strengthened at their junction by means of an outside fillet b^3 .

It may also be provided with an inside fillet b^4 , which will still further strengthen the structure.

C' and C^2 designate pieces of packing material or blocks, which may be of wood.

They are arranged on opposite sides of the rail-sections and preferably extend across adjacent ends of the same longitudinally, (designated by C' .) One of these pieces of packing material is arranged intermediate of the

upright or bolt plate b^2 of the angle-chair B' and the webs of the rail-sections A' A^2 .

The other piece of packing material (designated as C^2) is arranged intermediate the other sides of the webs of the rail-sections, and a metal bar or band, designated as D and which preferably will be made of rolled steel and extends across adjacent ends of the rail-sections

and approximately the length of the said pieces of packing material, is arranged contig-

uously thereto. E designates bolts for securing said parts together by passing through said upright of said angle-chair, said pieces of packing material, and said metal bar.

In order to prevent an electric current passing from one of the adjacent rail-sections to the other, it is necessary to insulate said sections and the above-mentioned parts, so as to insure a break for the stoppage of the current at least one point in each electric contacting part or parts, which would otherwise form an electrical connection between the two rail-sections. My preferred construction for accomplishing this result is as follows: Insulating material is arranged along the entire surfaces of both the upright and base or bridge plate of the angle-chair and intermediate not only said upright and the packing contiguous thereto, but said base and the base of the rail-sections. Such an insulator is designated in the drawings as F' and may, as there shown, extend continuously downwardly along the entire side of the upright and thence along the base of the angle-chair.

The ends of the adjacent rail-sections are insulated from each other by suitable means— as, for example, by insulating material K , as shown; but this is unnecessary when the rail ends are separated by an air-space.

The washers E' and E^2 , of insulating material, arranged intermediate the heads of the bolts and the upright and metal bar, respectively, and sleeves or bushings P , also of insulating material, surrounding the bolts, as shown, throughout that portion of said bolts which pass through said upright and said metal bar, insulate the bolts from both said bar and said upright.

It will be seen that according to my construction where all the bolt ends and heads are insulated current cannot pass from rail to rail through either the chair or metal bar without passing insulation at two points because of there being insulation between both rail ends and the bar and chair. This double insulation, though preferred, is not, therefore, essential.

Obviously some features of the invention may be used without other features and may

be embodied in widely-varying forms. Therefore, without enumerating equivalents or limiting myself to the construction shown and described,

5 I claim, and desire to obtain by Letters Patent, the following:

1. An insulated rail-joint, comprising a rail-chair having a bridge-plate and a bolt-plate, insulating material between the rail ends and 10 said bridge-plate, a metal band separate from said chair and opposing said bolt-plate and extending across the joint, two insulating-blocks one between said bolt-plate and the rail ends and the other between said band and 15 the rail ends and both extending across the joint, a plurality of bolts extending through the bolt-plate, insulating-blocks, rail ends, and band, insulating-bushings adapted to insulate every of said bolts passing through one 20 of the rail ends from both said bolt-plate and said band, and means for maintaining the rail ends from contact with each other, substantially as set forth.

2. In an insulated joint for railroad-rail sections, the combination of a rail-chair comprising a bridge-plate for supporting the rail ends and a bolt-plate at one side of the webs of the rail ends, a metal band arranged on the other side of the webs of the rail ends and 25 extending across the joint, packing material between the rail ends and said metal band and between the rail ends and the bolt-plate, bolts extending through the bolt-plate, packing material, webs of the rails and metal band, 30 means for insulating the bolts of at least one of the rail-sections from the metal band, means for insulating the bolts of at least one of the rail-sections from the bolt-plate, and means for maintaining the rail ends from contact 35 with each other, substantially as set forth.

3. In an insulated joint for railroad-rail sections, the combination of an angle-chair comprising a base for supporting the rail-sections and an upright at one side of the webs of the 40 rail-sections, a metal bar constructed independently of the angle-chair and arranged on the other side of the webs of the rail-sections and substantially parallel to the upright of said angle-chair and extending across the 45 joint of the rail-sections, bolts extending through said angle-chair and said bar for securing those parts together, and insulating material for the bolts, the upright of the angle-chair and the said metal bar for preventing electric communication between the 50 rail-sections, for substantially the purposes set forth.

4. In an insulated joint for railroad-rail sections, the combination of an angle-chair comprising a base for supporting the rail-sections and an upright at one side of the webs of the rail-sections, a metal bar constructed independently of the angle-chair and arranged on the other side of the webs of the rail-sections 55 and extending across the joint of the rail-sections, packing material on each side of the webs of the rail-sections extending across the

joint of the rail-sections, and arranged between the said upright and said metal bar, bolts for securing the parts together, and insulating material for the bolts for preventing electric communication between the rail-sections, for substantially the purposes set forth. 70

5. In a joint for railroad-rail sections, the combination of an angle-chair comprising a 75 base for supporting the rail-sections and an upright at one side of the rail-sections, a metal part constructed independently of the angle-chair and arranged on the other side of the webs of the rail-sections and substantially 80 parallel to the upright of said angle-chair and extending across the joint of the rail-sections, backing at each side of the rail-webs, and bolts extending through the upright of said angle-chair and said bar for securing the parts 85 together, and means for insulating the bolts of at least one of the rail-sections from both the angle-chair and the said metal part, for substantially the purposes set forth.

6. In an insulated joint for railroad-rail sections, the combination of an angle-chair comprising a base for supporting the rail-sections, and an upright at one side of the webs of the rail-sections, a metal bar constructed independently of the angle-chair and arranged on 95 the other side of the webs of the rail-sections and extending across the joint of the rail-sections, packing material intermediate of the rail-sections and said metal bar, and bolts for securing the parts together, for substantially 100 the purposes set forth.

7. In an insulated joint for railroad-rail sections, the combination of an angle-chair comprising a base for supporting the rail-sections, and an upright at one side of the webs of the 105 rail-sections, a metal bar constructed independently of the angle-chair and arranged on the other side of the webs of the rail-sections, packing material intermediate of the rail-sections and said metal bar and extending across 110 the joint of the rail-sections, and bolts for securing the parts together, insulated from the upright and the metal bar, for substantially 115 the purposes set forth.

8. In an insulated joint for railroad-rail sections, the combination of an angle-chair comprising a base for supporting the rail-sections, and an upright at one side of the webs of the rail-sections, a metal bar constructed independently of the angle-chair and arranged on 120 the other side of the webs of the rail-sections, packing material on each side of the rail-sections extending across the joint of the rail-sections, and bolts for securing the parts together, insulated from the upright and the 125 metal bar, for substantially the purposes set forth.

9. In an insulated joint for railroad-rail sections, the combination of an angle-chair comprising a base for supporting the rail-sections 130 and an upright at one side of the webs of the rail-sections, a metal bar constructed independently of the angle-chair and arranged on the other side of the webs of the rail-sections

and extending across the joint of the rail-sections, packing material intermediate of the rail-sections and said upright of the angle-chair, and bolts for securing the parts together, for substantially the purposes set forth.

10. In an insulated joint for railroad - rail sections, the combination of an angle - chair comprising a base for supporting the rail-sections, and an upright at one side of the webs of the rail-sections, a metal bar constructed independently of the angle - chair and arranged on the other side of the webs of the rail-sections and extending across the joint 15 of the rail-sections, packing material intermediate of the rail-sections and said metal

bar, and bolts extending through the metal bar and the rail-webs and the upright of the chair for securing the parts together, and means for insulating the bolts of at least one 20 of the rail-sections from the metal bar, means for insulating the bolts of at least one of the rail-sections from the chair, for substantially the purposes set forth.

In testimony whereof I have signed this 25 specification in the presence of two subscribing witnesses.

GEORGE A. WEBER.
